UNITED STATES PATENT OFFICE.

CLARKSON MENDENHALL, OF WILMINGTON, DELAWARE.

ROAD-SCRAPER.

SPECIFICATION forming part of Letters Patent No. 298,604, dated May 13, 1884.

Application filed March 1, 1884. (No model.)

To all whom it may concern:

Be it known that I, CLARKSON MENDENHALL, a citizen of the United States, residing at Wilmington, in the county of New Castle and State of Delaware, have invented new and useful Improvements in Road-Scrapers, of which the following is a specification.

The present invention relates to that class of road-scrapers in which is employed a scraper-board that extends across the road-bed in such a manner that it can be set at different angles in relation to the draft-pole.

The object of the invention is to provide a road-scraper board which, in addition to its capability of being set straight across the road-bed, can be inclined or set obliquely in opposite directions from a central draft-pole, and can be raised at either end to avoid obstructions or cause the scraping operation to be carried on only at one side of the machine. Furthermore, the scraping devices are capable of being raised entirely from the ground when clearing obstructions or when transporting the machine from place to place. Means are also provided for locking the scraper-board in either of the positions into which it is capable of being placed, and the adjustment of the board is performed from the driver's seat or platform without necessitating his descent therefrom.

The invention will first be fully described, and then pointed out in the claims.

Figure 1 is a plan view showing the scraper-board extending in a straight line across the road-bed. Fig. 2 is a similar view showing the scraper-board and its supporting-beams in position for holding said scraper-board obliquely across the road-bed. Fig. 3 is a view similar to Fig. 2, except that the scraper-board is shown oppositely inclined in relation to the road-bed. Fig. 4 is a side elevation of a road-scraper embodying my improvements, the parts being in position ready for work. Fig. 5 is a side elevation showing the scraper-board in a raised position and the machine supported solely upon the ground-wheels. Fig. 6 is a front elevation showing the draft-pole, whiffletree, and elliptical front bar or beam for supporting said draft-pole and whiffletree. Fig. 7 is a section taken through the scraper-board and supporting devices.

The letter A designates a draft pole or tongue, which is extended in a rearward direction, so as to constitute the central beam, A', of the supporting-frame of the scraper or machine. This pole A passes through a front beam or support, which consists of two semi-elliptical or curved bars, B, that meet at their ends, and are united thereat by vertical bolts a. The draft-pole passes through the center of the elliptical space left between these bars B, and a vertical bolt or pivot-pin, C, serves to connect it with both bars. A whiffletree, D, supported upon the bottom bar, B, is held in place by the bolt C, and can turn thereon. At the ends of the bars B or the front supporting-beams are arranged upwardly-projecting clevis rings or plates E, which receive the hooked front ends of longitudinal rods or bars F. The object of these clevis-rings is to permit the rods or bars fitted therein to turn thereon or therewith, and have a sufficient vertical play for the object hereinafter stated. The rods or bars F are generally made of metal, and serve to support the longitudinal side beams, G, beneath which the scraper-board H is hung. The front ends of these beams G are provided with sockets H', which encircle and clamp the rods or bars F, and are secured to the beams by clip-plates h, embracing said beams. At the rear ends also of these beams are located loops or staples a', through which the rods or bars F are passed to connect the beams and bars, so that they will move together. A transverse brace-rod, I, extending beneath the tongue or the beam continuation thereof, is connected to the front ends of the beams G, and serves to assist in holding the same in their proper relative positions.

The scraper-board H is of any preferred form or construction, and is connected with a depressed portion, A², of the beam continuation A' of the draft-tongue by means of a bolt, J, which is securely fitted in the top edge of the scraper-board, and projects through a slot, a², in said depressed portion A² of the draft-tongue or central beam of the machine. The scraper-board is also provided with round posts or tenons K, which project above the top edge thereof and extend through corresponding openings in the side beams, G, suitable keys and washers applied to the tenons

above the beams serving to hold the scraper-beam in place. The round tenons K are the upper continuations of standards L, which are secured to the rear face of the scraper-board, and are embedded or seated in the latter. The lower end of these standards L is made round or curved, and metallic eyes or clasp-plates M encompass these rounded portions, and are secured to the lower ends of 10 curved stocks N, which extend in a downward direction from the beams G. These stocks N have bifurcated top portions, which receive the beams, and suitable bolts pass through said bifurcated stocks and the beams for securing the same.

In rear of the stocks N, which may also be termed "braces" or "supports" for the scraper-board, are arranged metal frames or hangers O, in which are journaled small wheels 20c P, that are designed to run upon the ground when the scraper-board is raised, as will be hereinafter stated. The hangers or frames O are slotted or they are made of plates which extend on both sides of the beams G and terminate at the proper distance above the latter to serve as the point of attachment for the rearwardly-extending levers Q, the attachment of the hangers to the levers being rigid. The lower ends of the hangers are formed or otherwise provided with rigidly-attached forward-projecting portions O', pivoted to the stocks N, and thus the journals or pivots of the wheels P become the fulcrums for the hangers and levers O Q, so that if the lever Q be depressed 30 the portion O' of the hanger O will be elevated to raise the beam G. These levers are generally slotted and operate on curved racks R, rising from the beams G, these racks passing through the slots in the levers and the latter 40 being locked thereto by means of movable catches or bolts r. From the rear of the draft-tongue or the beam continuation thereof rises an arm, S, which supports a seat, S', for the driver or operator of the machine. The levers Q extend along the sides of said seat, so as to be within convenient reach of the driver, for the object hereinafter stated.

Below the driver's seat is arranged a platform, T, which serves as a foot-board for enabling 50 the driver to exert, when required, a proper downward pressure upon the machine, to hold the scraper-board in a proper operative position. This platform T is pivoted at its ends to brackets or hangers U, depending from the 55 rods or bars F, suitable bolts or screws passing through the platform and horizontal bottom portions of the hangers, constituting the pivots, which allow the platform or foot-board to turn. Perforated metal plates R', secured 60 to the top of the scraper-board, serve, in connection with a hooked rod, V, carried by the side beams, G, to hold the scraper-board in a proper working position.

Having described the construction of my 65 improved scraper, I will now set forth the mode of operation thereof.

When the scraper-board is in the position shown in Fig. 1, or is arranged straight across the road-bed, the side beams are parallel with each other, or, in other words, their front and rear ends are directly in line with each other, and the parts are locked in this position by the hooked rod V, entered into one of the perforations of the plates R' on the scraper-board. When the ground-wheels are in an 70 elevated position, the scraper-board is in contact with the ground for the proper performance of the scraping operation. In order to raise it entirely above the ground, the levers arranged within control of the driver are depressed, thus throwing the wheel-hangers downward and causing the machine to be supported upon the ground-wheels. By operating the levers at either side of the machine singly, either end of the scraper-board can be 75 elevated, so as to enable stones or obstructions to be properly cleared. In order to set the scraper-board at an oblique angle to the draft-pole, the side beams are thrown into the position shown in Fig. 2, or, if a reverse inclination of the scraper-board is desired, into the 80 position represented in Fig. 3.

It will be evident that the pivotal connection of the front elliptical support or bar, B, with the draft-pole and a similar connection 95 of the side beams with the scraper-board by means of the round tenons thereof will enable said beams to be moved longitudinally in relation to the central draft pole or beam, so as to permit the scraper-board to be set obliquely 100 in either direction in relation to the draft-pole or center beam. This movement of the scraper-board is also permitted by reason of the peculiar connection of the longitudinal rods or bars F with the clevis-plates on the 105 front elliptical beam or support and the clasp-plates of the pendent stocks or braces of the side beams encircling the round portions of the standards L, secured to the rear of the scraper-board. Moreover, the pivotal connection of the platform or foot-board with the 110 hangers or supports on the side beams is also necessary to allow the above-mentioned adjustments of the scraper-board to be effected.

It is evident that the engagement of the 115 hooked front ends of the bars or rods F with the clevises on the front bar or support, B, will allow said bars to be moved up or down independently of each other, and for this reason either side of the scraper-board can be raised 120 by the manipulation of the lever and wheel mechanism in the manner already described.

It has been stated that the scraper-board has upwardly-projecting tenons, which turn in 125 sockets in the side beams, and are held in place by keys and washers, and it may now be added that, if desired, I may apply springs or elastic washers to the portions of the tenons projecting above said scraper-board, in order to make an elastic connection between the 130 scraper-board and side beams and allow said scraper-board to have a sufficient vertical

movement independently of the adjustment effected by the lever and wheel mechanism.

I am aware that a road-scraper has been constructed of parallel longitudinal beams and 5 transverse bars carrying scraper-blades pivoted together in such a manner that said scraper-blades can be set at right angles to the road or at different angles in relation thereto.

Having thus described my invention, what 10 I claim is—

1. In a road-scraper, the combination of the central draft pole or beam, the pivoted cross-bar, the longitudinal rods or bars connected with the latter, the parallel shiftable 15 side beams, and the scraper-board pivotally connected with the central and side beams, substantially as described.

2. In a road-scraper, the combination of the scraper-board having upwardly-projecting 20 round tenons and rear posts or standards provided with rounded portions, and the inclined stocks having clasps encircling said rounded portions, with the parallel shiftable side beams and the central beam or draft-pole, substantially as described.

25 3. In a road-scraper, the combination of the pivoted foot-board or rear platform and the

shiftable side beams having brackets or hangers for supporting said foot-board, with the central beam, a draft-pole, and the scraper-board pivotally connected to the side and central beams, substantially as described. 30

4. In a road-scraper, the combination of the pivoted hangers and bearing-wheels journaled therein, and the levers or lifting devices connected with said hangers, with the shiftable side beams, the central beam or draft-pole, and the scraper-board pivotally connected therewith, substantially as described. 35

5. In a road-scraper, the combination of the 40 scraper-board having perforated catch-plates, and the shiftable side beam carrying hooked rods adapted to engage with said catch-plates, with the central beam, and second shiftable side beam pivotally connected with the scraper-board, substantially as described. 45

In testimony whereof I have hereunto set my hand in the presence of two subscribing witnesses.

C. MENDENHALL.
